UNITED STATES PATENT OFFICE.

LEO ROSEMAN, OF NEWARK, NEW JERSEY.

GARMENT-FASTENER MEANS.

Application filed December 22, 1926. Serial No. 156,474.

This invention relates, generally, to improvements in fastener means for garments, and more especially to a novel construction of fastener elements adapted for cooperation with hook-fasteners such as are commonly employed in connection with women's garments.

In my copending application for United States Letters Patent, Serial No. 119,851, filed on or about July 1st, 1926, I have shown and described a novel construction of fastener means adapted to operatively engage with hook-fasteners to separably fasten garment portions together, such fastener means comprising a pocket-forming strip suitably applied along one garment edge and so secured as to provide hook-bill receiving pockets entering under the inward edge and extending beneath the strip.

The present invention has for its principal object to provide an improved species of the above-mentioned type of fastener means, and to such end provides a novel construction and arrangement of means for reenforcing the pocket-forming strip at the points where the hook-bill receiving pockets are formed and located.

The invention has for a further object to provide a novel reenforcing means for the aforesaid hook-bill receiving pockets of the fastener means, which comprise rigid members, preferably made of metal, so arranged and associated with the pocket forming strip as not only to be concealed from the eye, so that the neat appearance of the fastener means is not marred, but also being so arranged that no part of the said reenforcing members is or can be exposed to contact with the wearer's person or with other garments of the wearer; and, furthermore, serving to enable the user to quickly locate the hook-receiving pockets by touch.

The invention is clearly illustrated in the accompanying drawings, in which:—

Figure 1 is a fragmentary view of the front portion of a garment, the opening of which is provided at one side with the novel fastener means, in tape form, to cooperate with the hook-fasteners provided at the opposite side of said garment opening. Figure 2 is an enlarged face view of a portion of the novel fastener means detached from the garment; Figure 3 is an inner edge view of the same; and Figure 4, is a transverse section through the same, taken on line 4—4 in said Figure 2. Figure 5 is a perspective

view of one form of the hook-receiving pocket reenforcing means; and Figure 6 is a perspective view of a modified form thereof. Figure 7 is a face view of a portion of the novel fastener means, the hook-receiving pocket having another modified form of reenforcing member associated therewith; and Figure 8 is a similar view illustrating still another modified form of hook-receiving pocket reenforcing member.

Similar characters of reference are employed in all of the hereinabove described views, to indicate corresponding parts.

Referring to the drawings, the reference character *a* indicates a garment body of any kind. Secured by stitching to the inner marginal portions of one meeting edge of the garment opening is a hook-tape *b* which is equipped with suitably spaced apart fastener hooks having their bills *c* exteriorly projected along the inner face of said meeting edge of the garment.

The reference character *d* indicates a base-portion of a fastener tape, a portion *d'* of which is preferably folded length-wise upon itself upwardly and forwardly over the same to strengthen it and at the same time provide a finished rear edge to said base-portion. The outer extension *e* of said base-portion is also folded lengthwise upon itself, thus providing an inturned section *e'*; such folded extension *e*—*e'* being turned upwardly and rearwardly over the outer surface of the base-strip *d*—*d'* to provide a pocket-forming strip or member bordering the outer marginal portion of the latter, the same being of a width substantially less than the width of said base-portion *d*—*d'*.

Disposed so as to lie intermediate said extension *e* and its inturned section *e'* providing the pocket-forming strip are reenforcing members longitudinally spaced apart in correspondence with the hook-bill receiving pockets to be formed in connection with said pocket-forming strip. Said reenforcing members may be made of any suitable substantially rigid material to provide reenforcing and pocket-lip forming bars extending longitudinally through the line of fold intermediate said extension *e* and inturned section *e'* coincident to the mouth of each hook-bill receiving pocket; said bar having at each end suitably formed abutments cooperating with the pocket forming stitching subsequently described, to retain said bars against displacement. Said reenforcing

members, therefore, are not only calculated to reenforce the hook-bill receiving pockets of the fastener means, but also serve to form a relatively rigid lip-portion at the mouth of each such pocket, over which a hook-fastener may snap to more securely hold the same against accidental separation or unhooking, and at the same time providing means whereby the user may more easily locate the pockets by touch without necessarily looking at the fastener means when engaging hooks therewith.

In the preferred form thereof, the rigid reenforcing members are made of metallic wire rectangularly shaped to provide a reenforcing and lip forming bar α , from the opposite ends of which extend abutment forming side bars γ terminating in a base-bar α parallel to said bar α . It will be understood that such formation of reenforcing member need not necessarily be made of metallic wire, since it may be provided in the form of a stamping of metal, fibre or any other substantially rigid material, if so desired. As applied to the base-portion and pocket forming strip, the reenforcing member, in the above described form thereof, is disposed at the pocket locations so that the reenforcing and lip-forming bar α lies in the fold of the extension e and its inturned section e' to border the mouth of the pocket to be served thereby, while its base-bar α lies in the fold of the base-portion d and extension e , with sides γ forming abutments cooperating with the pocket forming stitching subsequently to be described. It will be obvious from an inspection of Figures 1, 2 and 4 of the drawings, that the above described preferred form of reenforcing member not only reenforces the edge of the pocket forming strip bordering the mouth of the hook-bill receiving pocket with which it is associated, but also serves to transversely reinforce the pocket forming strip at each pocket location, since its base-bar α possesses a footing or purchase against the outer free folded edge of the base-portion d and pocket forming strip extension e whereby, through the interconnecting side bars γ , the reenforcing bar α is braced against the pulling strain of a hook-fastener operatively engaged or coupled with the pocket forming strip when the fastener means is in use; thus relieving both the fabric of the pocket forming strip at the mouth of the hook-bill receiving pocket, as well as the pocket forming stitching from necessity of sustaining the entire strain of the pull of said engaged hook-fastener. It will be apparent, therefore, that for uses in connection with which an unusually strong fastener means is desirable, the above described species of reenforcing member is preferable; although more simple forms of such reenforcing members, such as herein-after referred to, may also be employed,

within the broader aspects of the present invention; in fastener structure wherein transverse reenforcement of the pocket forming strip is not especially essential.

After the parts of the fastener tape have been formed and co-related, and the reenforcing members assembled therewith, in the manner above set forth, a series of longitudinally spaced pockets g opening along the free edge of the pocket forming strip or member are provided, the spacing of which is arranged to correspond to the spacing of the fastener hook-bills c of the hook-tape b to be served. The said pockets g are formed by sewing down the free edge of said pocket forming strip or member to the main body or base-portion $d-d'$ of the tape by a line of stitches h , the same being interrupted at intervals so as to terminate adjacent to the sides of the pocket positions, at which points are formed a plurality of transversely extended tying stitches i which extend outwardly across the free edge of the pocket forming strip. These tying stitches i also traverse the ends of reenforcing and lip forming bar α at points adjacent to the juncture of the latter with the abutment forming side bars γ , and consequently, not only do said tying stitches strongly reenforce the union of the pocket forming strip or member with the base-portion $d-d'$ at each side of the pocket g , but also serve to retain the reenforcing members in operative position and relation to the pocket g , since the abutment of said side bars γ upon said tying stitches i firmly holds the reenforcing members against shifting longitudinally out of their proper placement. Since the stitching, including the longitudinal stitches h and transverse tying stitches i are preferably formed by suitable machines as a continuous line of stitching, intermediate each set of side bounding tying stitches i and preferably rearwardly off-set beyond the mouth of the formed pockets interconnecting jump stitching j may be provided either in the form of a plurality of stitches as shown in the accompanying drawing, or in the form of a single intermediate jump stitch, as shown in my above-mentioned co-pending application. It will of course be obvious that several variations in form and arrangement of the run of longitudinal stitches h , tying stitches i and jump or intermediate stitches j may be possible, and consequently I do not limit myself solely to the particular arrangement and form thereof which is shown in the accompanying drawings and which is above described.

Referring now to Figure 6 of the drawings, I have shown therein a reenforcing member of the same general character as that already above described, except that the reenforcing and lip-forming bar instead of being straight is provided with a slightly

upwardly arched or bowed formation indicated at α' . This form of reenforcing member possesses the slight advantage of producing a preformed mouth opening at the entrance of each hook-bill receiving pocket.

Referring furthermore to Figure 7 of the drawings, I have shown therein a modified form of reenforcing member, comprising a reenforcing and lip-forming bar α^2 having at its ends doubled back portions y' forming stops or abutments. When such type of reenforcing member is employed, one of the same is disposed at each pocket location so that the reenforcing and lip-forming bar α^2 lies in the fold of the extension e and its inturned section e' to border the mouth of the pocket to be served thereby, and so that the tying stitches i of the pocket forming stitching traverse the ends of the box α^2 at points adjacent to the stops of abutments y' , which by engagement with the tying stitches prevent longitudinal displacement of this form of reenforcing member.

Referring to Figures 8 of the drawings, I have illustrated thereby a still further modified form of reenforcing member, comprising a reenforcing bar α^3 having at its end inwardly off-set portions y'' forming abutment shoulders s . When this type of reenforcing member is used, one of the same is disposed at each pocket location so that the reenforcing and lip-forming bar α^3 lies in the fold of the extension e and its inturned section e' to border the mouth of the pocket to be served thereby, and so that the tying stitches i of the pocket forming stitching traverse the ends of said bar α^3 at points adjacent to the abutment shoulders s , which by engagement with said tying stitches prevent longitudinal displacement of this form of reenforcing member.

It will be evident that variations in the forms of said reenforcing members other than those already above referred to may be made, hence I do not limit myself to any specific form thereof except in so far as such limitations are specified in the subsequent claims.

In the accompanying drawings I have shown the instant invention of fastener means embodied in fastener tape form; I desire it to be understood, however, that the features thereof, which are especially related to the provision of the novel character of pocket reenforcing members in connection therewith, may be employed with pocket forming strips directly formed from the marginal body of the garment material or in connection with a combined fastener tape and garment edge binding, both of which types of fastener means having the hook-bill receiving pockets are fully described and shown in my aforesaid copending application for Letters Patent.

Having thus described my present invention, I claim:

1. A garment fastener means separably engageable by hook-fasteners, comprising a pocket forming strip having a longitudinally folded inner edge, means upon which said pocket forming strip is applied, stitching to secure said edge to said means upon which said strip is applied, said stitching being interrupted at intervals to form hook-bill receiving pockets entering under said edge and beneath said strip, and a rigid reenforcing and pocket-lip forming member within the free portion of said folded edge bounding each pocket, said reenforcing member having means cooperating with said stitching to prevent its displacement. 75

2. A garment fastener means separably engageable by hook-fasteners, comprising a pocket forming strip having a longitudinally folded inner edge, means upon which said pocket forming strip is applied, stitching to secure said edge to said means upon which said strip is applied, said stitching being interrupted at intervals to form hook-bill receiving pockets entering under said edge and beneath said strip, a rigid reenforcing and pocket-lip forming member within the free portion of said folded edge bounding each pocket, transverse tying stitches at each side of each pocket and traversing the end portions of said reenforcing member, said reenforcing member having means cooperating with said tying stitches to prevent its displacement. 80

3. A garment fastener means separably engageable by hook-fasteners, comprising a base, a pocket forming strip on said base having its outer edge portion joined with said base and having a longitudinally folded inner edge, stitching to secure said inner edge to said base, said stitching being interrupted at intervals to form hook-bill receiving pockets entering under said inner edge and beneath said strip, a rigid reenforcing member underlying said strip at each pocket location, said reenforcing member comprising a reenforcing and lip-forming bar within the free folded edge of said strip bounding each pocket and side members terminating in means abutting the juncture of the outer edge of said strip with said base, and means to prevent displacement of said reenforcing member. 105

4. A garment fastener means separably engageable by hook-fasteners, comprising a base, a pocket forming strip on said base having its outer edge portion joined with said base and having a longitudinally folded inner edge, stitching to secure said inner edge to said base, said stitching being interrupted at intervals to form hook-bill receiving pockets entering under said inner edge and beneath said strip, a rigid reenforcing member underlying said strip at each 115

pocket location, said reenforcing member comprising a reenforcing and lip-forming bar within the free folded edge of said strip bounding each pocket and side members terminating in means abutting the juncture of the outer edge of said strip with said base, and transverse tying stitches at each side of each pocket and traversing the end portions of said reenforcing and lip-forming bar adjacent to said side members.

5. A garment fastener tape having longitudinally spaced pockets rearwardly open relative to its outer edge and separably engageable by the bills of opposed hook fastener means, comprising a main body, a pocket forming strip having a folded inner edge overlying said main body to extend inwardly from the outer portion of the latter, stitching for interruptedly securing the inner edge portion of said strip to form at the points of interruption said hook-bill receiving pockets so that the latter enter under said edge and beneath said strip, a rigid reenforcing and pocket-lip forming member within the free portion of said folded edge bounding each pocket, transverse tying stitches at each side of each pocket and traversing the end portions of said reenforcing member, said reenforcing member having means cooperating with said tying stitches to prevent its displacement.

6. A garment fastener tape having longitudinally spaced pockets rearwardly open relative to its outer edge and separably engageable by the bills of opposed hook fastener means, comprising a main body, a pocket forming strip having a folded inner edge overlying said main body to extend inwardly from the outer portion of the latter, stitching for interruptedly securing the inner edge portion of said strip to form at

the points of interruption said hook-bill receiving pockets so that the latter enter under 40 said edge and beneath said strip, a rigid reenforcing and pocket-lip forming member within the free portion of said folded edge bounding each pocket, transverse tying 45 stitches at each side of each pocket and traversing the end portions of said reenforcing member, said reenforcing member having means cooperating with said tying stitches to prevent its displacement.

7. A garment fastener tape having longitudinally spaced pockets rearwardly open relative to its outer edge and separably engageable by the bills of opposed hook fastener means, comprising a main body, a pocket forming strip at the outer edge of 55 said main body, said strip being longitudinally folded rearwardly over the latter, said strip having an inturned folded inner edge portion, stitching to secure the inner edge of said strip to said underlying main body, 60 said stitching being interrupted at intervals to form rearwardly open hook-bill receiving pockets entering under the inner edge of and beneath said strip, a rigid reenforcing member underlying said strip at each pocket 65 location, said reenforcing member comprising a rigid pocket frame extending between the folded inner edge of said strip and the folded outer edge of said main body, and transverse tying stitches at each side of each 70 pocket and traversing portions of said pocket frame to prevent its displacement.

In testimony, that I claim the invention set forth above I have hereunto set my hand this 14th day of December, 1926.

LEO ROSEMAN.
